CLAIM

The ornamental design for an electronic device finger grip, as shown and described.

DESCRIPTION

FIG. 1 is a left perspective view of the electronic device finger grip of the present invention, shown with the hand grip in the down position;

FIG. 2 is a right perspective view thereof;

FIG. 3 is a perspective view illustrating the back surface;

FIG. 4 is a front view thereof;

FIG. 5 is a back view thereof;

FIG. 6 is a side view thereof, with the handgrip rotated away from the viewer;

FIG. 7 is a side view thereof, with the handgrip rotated toward the viewer;

FIG. 8 is a top view thereof;

FIG. 9 is a bottom view thereof;

FIG. 10 is an environmental view of the electronic device finger grip secured to a cell phone and resting on a table, shown with the hand grip in the lifted position; and,

FIG. 11 is an environmental view of the electronic device finger grip secured to a cell phone and shown placed in a hand of a user.

The portions of the electronic device finger grip and the environment in FIGS. 10 and 11 illustrated in broken lines form no part of the claimed subject matter. The dash-dot-dash broken lines shown in the figures represent the bounds of the claim and form no part thereof.
